UNITED STATES PATENT OFFICE.

MATTHEW S. EYLAR, OF NEW YORK, N. Y., ASSIGNOR TO ELLIOTT & HATCH
BOOK TYPEWRITER COMPANY, A CORPORATION OF NEW YORK.

TYPE-WRITING MACHINE.

SPECIFICATION forming part of Letters Patent No. 732,840, dated July 7, 1903.

Application filed February 16, 1903. Serial No. 143,560. (No model.)

To all whom it may concern:

Be it known that I, MATTHEW S. EYLAR, of New York city, county of New York, and State of New York, have invented a new and 5 useful Improvement in Type-Writing Machines, of which the following is a specification.

My invention has reference more particularly to type-writing machines wherein a flat 10 platen is employed to sustain the paper beneath an overlying writing mechanism arranged to print in a downward direction thereon and to shift horizontally for letter and line spacing—such, for example, as the Elliott & Hatch machine of commerce, represented as 15 to its general organization in Letters Patent of the United States No. 620,125. It is desirable to adapt these machines to print two alphabets of capital letters, one having a large 20 or broad face and the other a smaller or narrower face. When these two faces are used in the one machine, it is desirable to have a feed mechanism which may be instantly adjusted to feed the carriage or printing mechanism forward uniformly step by step the 25 distance required for the wide letters or uniformly step by step for a smaller distance suitable to the narrow letters.

To this end I combine with the letter-feed 30 mechanism in a machine having an alphabet of wide characters and a second alphabet of narrow character devices which may be instantly thrown into or out of action to control the distance which the carriage advances between the printing of one letter and the next.

In all parts except the feed mechanism the 35 machine may be of ordinary construction.

In the drawings, I have represented my improvement as applied to an Elliott & Hatch 40 machine, the drawings being limited to the feed mechanism and adjacent parts necessary to an understanding of its action.

Figure 1 is a perspective view of the rear 45 part of a machine with my improved feed devices applied thereto. Figs. 2 and 3 are rear elevations of the feed-dogs, feed-wheel, and adjacent parts; and Fig. 4 is a vertical cross-section through said parts on the corre-

spondingly-numbered line of the preceding figures. Fig. 5 is a diagrammatic view showing the relative spacing of the large and small capital letters.

Referring to the drawings, A represents the traveling frame or carriage of the machine in which the series of type-bars B are 50 mounted on pivots at their lower ends and connected with finger-keys, as usual, whereby they are caused to swing downward and print on the underlying sheet of paper. There will be the usual series of these type-bars arranged in a circle to strike at a common central point, and each bar will be provided at the upper end with the usual rocking head C, carrying two type D and D', one or the other of which may be brought into the printing position by rocking the head through the usual devices provided for the purpose. One of the letters of the type B is of large size, with a broad face, while the other, having the same character or letter of a different series 55 or font, has a smaller and narrower face. Both alphabets will be composed of capital letters. In using the machine, matter will be printed at one time entirely from the small type and at another time entirely from the 60 large type. After each printing action the carriage should advance laterally a distance corresponding to the width of the type in action. This variable feed of the frame is effected as follows: The carriage, suitably 65 supported and guided on rollers, is urged constantly to the left by the usual spring connections. Its advance is controlled by the toothed rack F on the horizontal fixed guide-bar G. This rack is engaged by a pinion H, 70 having its horizontal shaft mounted in the carriage and provided with a toothed escape- 75 ment-wheel I. This wheel is controlled in its rotation by the two alternately-acting dogs J and K, carried by the rocker-frame L, mount- 80 ed to vibrate at right angles to the direction in which the carriage advances. The dog J is fixed to the rocker-frame. The dog K is pivoted at k to the rocker-frame, so that its upper end which engages the wheel may vi- 85 brate in the direction in which the frame 90

travels. It is acted upon at the lower end by spring k' , which tends to throw the upper end forward out of line with the other dog and ahead of the same in the direction in which 5 the machine advances. The escapement-wheel has a tendency to rotate in the direction indicated by the arrow.

In the normal condition of the parts the dog K is in engagement and is held back by 10 the pressure-wheel somewhat in advance of the fixed dog J, as shown in Fig. 2. When the rocker-frame is actuated by the operation of a finger-key or the space-key, it swings backward, carrying the upper end of the dog 15 K rearward out of engagement with the escapement-wheel I and at the same time bringing the dog J into the path of the wheel to arrest its rotation. The dog K when released, as stated, is thrown forward by the action of 20 the spring k' , as indicated by dotted lines in Fig. 2, so that when the two dogs are swung forward edgewise by the rocker-frame the dog J will disengage from and release the escapement-wheel, which will turn forward with the 25 pinion and permit the carriage to advance the space of one letter. The advance is arrested by the dog K, which during the forward motion of the rocker and the disengagement and retreat of dog J is carried in its 30 advanced position into the path of the escapement-wheel, so that the next tooth on the latter acting on the dog K will carry the latter to the right around its pivot k until its upper end is arrested by contact with the 35 shoulder on the rocker in its original position, the dog thus stopped in its vibration serving in turn to stop the wheel.

The foregoing action of the parts is similar to that of the feed-dogs in the ordinary Elliott 40 & Hatch machine. The distance which the carriage is permitted to move by each engagement and disengagement of the dogs depends on the distance which the dog K turns forward around its pivot k before engaging the 45 wheel. In Fig. 1 it is represented as swinging forward the distance of one tooth only, so that the escapement-wheel turns one tooth only, allowing the carriage to advance the width of one of the narrow type. If, however, the dog K is allowed to swing forward, 50 as shown in Fig. 3, the distance of two teeth, or, in other words, given a greater vibration, it will advance the distance of two teeth on the wheel and allow the wheel to turn the 55 distance of two teeth, the carriage being permitted to advance twice as fast as in the first instance a distance corresponding to the width of the wide type. In other words, the 60 advance of the carriage after each printing action is greater or less, according to the distance which the dog K is permitted to swing ahead before reengaging the escapement-wheel. In order to control this action, I combine with the dog K an adjustable stop device 65 under the control of the operator. I return the upper end of the spring k' above the

lower end of the dog K to serve as a stop therefor to check its vibration, as shown in Figs. 2 and 3. This end of the spring is extended through a plate M, mounted to vibrate vertically around a pivot-pin N on the yoke under the control of a rod O, connected at the upper end to a lever P, which is pivoted at p on the carriage and extended at its forward end within convenient reach of the operator 70 and past a dog or a latch Q, by which it may be locked down at will. When this lever is depressed and fastened down, it holds the plate M in its uppermost position, permitting the end of the spring or stop k' to stand in its 80 uppermost position, as indicated in Fig. 3. The effect of this is to permit the extreme vibration of the dog K and the corresponding extreme feed of the carriage. When the lever P is released, the plate M is pulled down 85 by the action of the spring k' and the upper end of the spring depressed, as shown in Fig. 2, so that it serves to limit the vibration of the dog K, and thus cause the short feed of the 90 carriage.

It will be observed that the upper end of the spring is, in fact, simply an adjustable stop to control the vibration of dog K, and it will be manifest to the skilled mechanic that this stop may be made in any other suitable form 95 and arranged in any suitable manner, provided only it is adapted to vary the extent of the vibration of the dog K and to be secured in position so that the feed of the carriage will be uniformly and constantly wide or narrow, according as the larger or smaller faces are called into use.

In operating the machine if the large type are required the type-shifting devices are adjusted to so control the position of the type-head C that the large type only will print. At the same time the lever P is locked down, thus causing the dog K to receive the maximum movement, so that the carriage will advance after each printing action a space 105 appropriate to the width of the large type. When, on the other hand, the small type alone are to be used, the lever P is released and the stop permitted to fall, so as to limit the movement of dog K, whereupon the machine will feed after the writing of each small type a correspondingly short distance.

It is to be noted that my invention does not relate merely to a feed mechanism having a variable action, but that it consists in 115 an organized machine carrying two distinct alphabets or fonts of type, each adapted to be used independently of the other, so that the writing may be effected wholly in one face or the other, the machine being adapted 125 to space uniformly and constantly for all the faces in each alphabet a distance appropriate to the alphabet which is at the time in use.

What I claim as my invention is—

1. A type-writer for producing two distinct 130 classes of print, comprising in combination an alphabet of wide characters and a distinct

alphabet of narrow characters, each usable independently of the other, and a letter-feed mechanism, adjustable to give a uniform and narrow feed or a uniform and wide feed, according as one alphabet or the other is in use.

2. In a type-writing machine, a series of type-bars with rocking heads, an alphabet of narrow type and an alphabet of wide type, one of each carried by each type-head, a letter-feed mechanism, means for varying the extent of the feeding action, and means for locking the parts, substantially as described,

whereby a uniform and narrow feed is effected when the narrow alphabet is in use, and a uniform and wide feed effected when the wide alphabet is in use.

In testimony whereof I hereunto set my hand, this 13th day of February, 1903, in the presence of two attesting witnesses.

MATTHEW S. EYLAR.
